G. L. T. DENNIS,
REVOLVING CHESSBOARD AND THE LIKE,
APPLICATION FILED MAR. 27, 1920.

1,374,139.

Patented Apr. 5, 1921.

INVENTOR.

George Lake Tallott Dennis.

UNITED STATES PATENT OFFICE.

GEORGE LAKE TALBOT DENNISS, OF LONDON, ENGLAND.

REVOLVING CHESSBOARD AND THE LIKE.

1,374,139.

Specification of Letters Patent.

Patented Apr. 5, 1921.

Application filed March 27, 1920. Serial No. 369,883.

To all whom it may concern:

Be it known that I, GEORGE LAKE TALBOT DENNISS, lieut.-colonel, (retired,) a subject of the King of Great Britain and Ireland, 5 residing at London, England, have invented certain new and useful Improvements in Revolving Chessboards and the like; and I do hereby declare the following to be a full, clear, and exact description of the invention, such as will enable others skilled in the art to which it appertains to make and use the same.

This invention relates to a new or improved revolving chess board and has for 15 its object to enable one or more than two players to move the board into such a position that the movements of the chessmen can be effected and the position of the opponent's chessmen judged without the player or players moving, while the chessmen are preferably secured against displacement when the board is rotated.

According to the invention the chess board is adapted to be secured to the upper surface of a table or disk adapted to rotate 25 about a vertical axis. The table may be round or rectangular in shape and is provided with one or more slideable or pivotal clips, which may or may not be spring controlled, said clips being preferably four in 30 number, adapted to engage the four outer edges of the chess board. The table or disk has secured to its under surface a stud or pin adapted to extend downwardly and form 35 a running fit in a sleeve or bush secured to the upper surface of a stand or frame of suitable construction.

In order that the table may be freely rotated, the top of the stand or frame is provided with a plurality of rollers or the like, 40 preferably four in number and arranged radially of the central axis of the rotatable table.

The upper surface of the chess board may 45 be provided with studs or projections arranged centrally within each square, said studs being arranged to engage a recess formed in the bottom of each of the chessmen, so as to prevent the latter becoming 50 displaced when the board is rotated.

In order that the invention may be readily understood reference is made to the accompanying drawings forming part of the specification in which:—

55 Figure 1 is a plan view of the rotatable table, with chess board removed therefrom.

Fig. 2 is a vertical section showing the chess board in position.

Figs. 3 and 4 are perspective views of the stub and socket secured to the rotating table 60 and its supporting frame respectively.

Figs. 5 and 6 are section and plan views respectively of one form of fastening means for securing the chess board to the table.

Fig. 7 is a view of a modified form of 65 fastening means.

Fig. 8 is a perspective view of the base of one of the chess men, while

Fig. 9 is a perspective view of part of the chessboard.

The apparatus consists of a circular or rectangular table or disk *a* to the under surface of which is attached a stub or pin *b* preferably formed with a flange *b*¹ by which it is secured to the table by screws. 70 This stub forms a running fit in a socket member *c* having a flange *c*¹ by which it is secured to the upper surface of a frame or stand *d*.

The rotating table *a* is further supported 80 by a series of rollers *e* located between the under surface of the table *a* and the top of the stand or frame *d*. Each of these rollers is mounted in brackets *e*¹ and arranged to rotate about a horizontal axis extending radially from the center of the table *a*. In the construction illustrated I have shown four supporting rollers each disposed equidistant from the central axis of the table *a* and from each other, the axis of each roller 90 being at right angles to the axes of the rollers on each side thereof.

The rollers are preferably of considerable length, say for instance of a length equal to one quarter of the diameter of the table 95 *a*, so as to form a steady and effective support for the table during its rotation.

The chessboard *f* is adapted to rest upon the upper surface of the table *a* and the latter is preferably provided with fastening 100 means for securing the chess board in position.

The fastening means may comprise four slideable or pivotal clips which may or may not be spring controlled, and they are preferably arranged so as to engage the four edges of the chess board, as shown in Fig. 1. One form of slideable clip is shown to an enlarged scale at Figs. 5 and 6. The upper surface of the table is provided with suitable radial recesses or grooves *h* in which is slideably mounted a member *k* bent over at 105 110

its outer end k^1 to form a clip or the like to engage the edge of the chess board. The member k is provided with a longitudinal slot k^2 through which project two pins or buttons m , each driven into the material of the table in such a position as to limit the extent of movement of the member k . With this form of fastening each of the clips are moved outwardly, and after the chess board has been placed in position the members are pushed in until their bent over ends k^1 engage the edge of the board.

In the modified construction of fastening shown in Fig. 7 the clips comprise an L shaped member n pivotally mounted on a support o driven into the outer edge of the table a , the support o may be in the form of a staple of U-shape, the member n being mounted on the central portion connecting the parallel limbs. The member m is adapted to be maintained in either of its extreme positions by a spring p the free end of which bears against the curved surface of the member n as shown in Fig. 7, the two extreme positions being shown in full and dotted lines respectively. With this form of fastening each of the clips are moved to the position shown in full lines, the chess board f is placed in position on the table a and the clips rotated in the direction of the arrow to the position shown in dotted lines.

In order to afford additional support to the chessmen when on the chess board, each square of the latter is preferably provided with a stud or projection q adapted to engage a corresponding recess r^1 in the base r of each of the chessmen, as shown in Figs. 8 and 9.

If desired the rotating table or disk a may itself constitute the chess board.

Suitable means may, if necessary be provided for holding the table against rotation, such means being operated to release the table when it is desired to rotate the same, but in practice such locking means will not be found necessary.

The details of construction may be modified, if desired, without departing from the principle of the invention.

What I claim and desire to secure by Letters Patent of the United States of America is:—

1. A revolving chess board, comprising a supporting frame, a rotatable table on said frame adapted to rotate about a vertical axis, members mounted rotatably between the upper surface of such frame and the under surface of said table, and fastening means on said table for securing the chess board thereto, for the purposes described.

2. A revolving chess board comprising a supporting frame, a table on said frame, a

stub secured to the under surface of said table, a socket secured to the upper surface of said frame in which said stub forms a running fit, rollers mounted between said frame and said table and arranged radially relatively to the axis of rotation, and fastening means for securing a chess board to said table for purposes described.

3. A revolving chess board, comprising a supporting frame, a socket secured centrally at the top of said frame, brackets arranged equidistant from said socket and from each other, rollers mounted in said brackets adapted to rotate about axes extending radially from said socket, a table above said frame, a stub secured to the underside of said table forming a running fit in said socket when supported by said rollers, and clips arranged equidistant from the central axis and from each other for engaging the edges of a chess board, for the purposes described.

4. A revolving chess board comprising a supporting frame, a table mounted rotatably on said frame so as to rotate about a vertical axis, rollers arranged radially of said axis and adapted to support said table at points equidistant from its central axis; and a plurality of radially movable clips arranged to be moved in one position to engage the edges of a chess board and to be moved to another position to enable said chess board to be removed from said table, for the purposes described.

5. A revolving chess board comprising a supporting frame, a table rotatable about a vertical axis on said frame, rollers disposed radially and adapted to support said table at points equidistant from its central axis, grooves in the upper surface of said table and extending radially inward from its outer periphery, slideable members mounted in said grooves, clips at the outer ends of said slideable members adapted to grip the edges of the chess board and means for limiting the extent of movement of the said slideable members for the purposes described.

6. A revolving chess board, comprising in combination a supporting frame, a table rotatable about a vertical axis on said frame, rollers disposed radially between said frame and the under surface of said table and adapted to support said table at points equidistant from its central axis, a chess board on said table, means for securing said chess board in position, studs on each of the squares on said board and a set of chessmen, each formed with a recess in its base adapted to engage said studs, for the purposes described.

In witness whereof I affix my signature.

GEORGE LAKE TALBOT DENNIS,
